US00D971506S

(12) **United States Design Patent** (10) **Patent No.:** **US D971,506 S**
(45) **Date of Patent:** **** Nov. 29, 2022**

(54) **ARTIFICIAL EYELASH EXTENSION
APPLICATOR**

(71) Applicant: **Lashify, Inc.**, North Hollywood, CA (US)

(72) Inventor: **Sahara Lotti**, North Hollywood, CA (US)

(73) Assignee: **Lashify, Inc.**, North Hollywood, CA (US)

(**) Term: **15 Years**

(21) Appl. No.: **29/741,638**

(22) Filed: **Jul. 14, 2020**

Related U.S. Application Data

(60) Division of application No. 29/703,954, filed on Aug. 30, 2019, now Pat. No. Des. 890,430, which is a continuation of application No. 29/692,817, filed on May 29, 2019, which is a division of application No. 29/667,344, filed on Oct. 19, 2018, now Pat. No. Des. 850,715, which is a continuation-in-part of application No. 15/968,453, filed on May 1, 2018, now Pat. No. 10,638,826, which is a continuation-in-part of application No. 15/968,361, filed on May 1, 2018, now Pat. No. 10,660,388, which is a continuation of application No. PCT/US2017/067513, filed on Dec. 20, 2017, which is a continuation of application No. PCT/US2017/044217, filed on Jul. 27, 2017.

(57) **CLAIM**

An ornamental design for an applicator for artificial eyelash extensions, as shown and described.

DESCRIPTION

FIG. 1 is an illustration of a front perspective view of an applicator for artificial eyelash extensions;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top view thereof;

FIG. 7 is a bottom view thereof; and,

FIG. 8 is a bottom perspective view thereof.

None of the broken lines form any part of the claimed invention.

1 Claim, 5 Drawing Sheets
